THERMAL PREPARATION OF ALKYLAMIDES

BACKGROUND OF THE INVENTION

This invention relates to a novel method of preparing alkylamides from alpha-nitroketones. In particular, it relates to a thermal non-catalytic method for preparing alkylamides from terminal alpha-nitroketones.

Alkylamides have previously been prepared by the amination of carboxylic acids. Many carboxylic acids, however, are not easily available in commerce and particularly those acids containing an odd numbered carbon chain. To prepare the acids, moreover, requires costly processing as by oxidizing the corresponding alcohol or by Grignard synthesis. Another method of preparing alkylamides is by converting nitro-nitrosoalkane dimers by reaction with at least molar amounts of an anhydrous mineral acid over relatively short contact times. However, this method is not commercially attractive inasmuch as the mineral acid is consumed during the reaction and low concentrations of the acid reactant must be employed so as to avoid explosive conditions.

A novel method has now been discovered whereby alkylamides having from 2 to 51 carbons can be provided in good yields.

SUMMARY OF THE INVENTION

Broadly, this invention contemplates a method of preparing an alkylamide which comprises contacting an alpha-nitroketone with an oxygenated polar aprotic solvent at a temperature of about 70° to 200°C. The transformation produces carbon dioxide as a by-product.

According to our invention the alpha-nitroketone thermally converted to the alkylamide is a terminal vicinal nitroketone and corresponds to the formula:

where R is an alkyl group having 1 to 50 carbon atoms. It is essential to the method of this invention that terminal alpha-nitroketones, i.e., 1-nitro-2-alkanones, be employed. Non-terminal alpha-nitroketones, that is nitroketones where the nitro group is on other than a terminal carbon, do not undergo thermal conversion to alkylamides as herein more fully described.

The method of the invention is further explained by the following equation:

where R is as heretofore defined and where a by-product of the method is carbon dioxide. It will be observed that the alkylamide possesses one carbon less than the starting nitroketone such that the conversion reaction involves transformation of the nitroketone through rearrangement and cleavage.

According to this invention the contemplated alkylamides are derived from alpha-nitroketones corresponding to the formula above and include as starting materials 1-nitro-2-propanone, 1-nitro-2-butanone, 1-nitro-2-pentanone, 1-nitro-2-hexanone, 1-nitro-2-heptanone, 1-nitro-2-octanone, 1-nitro-2-decanone, 1-nitro-2-

dodecanone, 1-nitro-2-pentadecanone, 1-nitro-2-hexadecanone, 1-nitro-2-heptadecanone, and 1-nitro-2-eicosanone. Mixtures of the alpha-nitroketones can be converted to the corresponding mixture of amides. The nitroketones contemplated as starting materials and listed above can be prepared in accordance with the procedures described in the art as, for example, in U.S. Pat. No. 3,557,166.

In one embodiment, the method of this invention comprises heating the nitroketone as hereinabove described at a temperature of about 70° to 200°C. in the presence of an oxygenated polar aprotic solvent. The class of solvents employed in the instant method is a key factor in the reaction. Hydrolytic solvents, that is polar protic solvents, such as alcohols or water produce products other than alkylamides such as esters or acids and nitroalkanes. No reaction occurs under the operating conditions described herein when non-polar solvents, such as benzene, hexane and toluene or non-oxygenated polar aprotic solvents such as methylene chloride, chloroform and 1,2-dichlorobenzene are employed.

The contemplated oxygenated polar aprotic solvents employed herein are illustrated by alkylformamides, alkylacetamides, alkylsulfoxides, alkylureas, alkylphosphoramides, alkylpyrrolidinones, aldehydes, ketones and ethers.

Specific examples of the solvents employed in the instant method are dimethylformamide, diethylformamide, dimethylacetamide, dimethylsulfoxide, diethylsulfoxide, tetramethylurea, tetraethylurea, hexamethylphosphoramide, 1-methyl-2-pyrrolidinone, 1-ethyl-2-pyrrolidinone, 1,4-dimethyl-2-pyrrolidinone, butyraldehyde, acetone, methylethylketone, diethylether, 1,4-dioxane, tetrahydrofuran and tetrahydropyran. Mixtures of oxygenated polar aprotic solvents can also be used. A highly preferred oxygenated polar aprotic solvent is dimethylsulfoxide. In general, any oxygenated aprotic solvent that is a liquid under the processing conditions set forth herein can be employed.

The mole ratio of nitroketone oxygenated polar aprotic solvent employed in the instant method is an important factor insofar as providing substantial yields of alkylamide. Suitably, the mole ratio of nitroketone to oxygenated polar aprotic solvent employed herein ranges from about 1:3 to 1:100, preferably from 1:10 to 1:50. An inert liquid diluent can be employed, if desired, to promote the contact of the nitroketone and oxygenated polar aprotic solvent. A suitable inert liquid diluent is one having a boiling point between about 80° and 200°C., such as heptane, chlorobenzene, ethylbenzene, cumene, cymene and durene.

The reaction temperature employed in the method wherein terminal alpha-nitroketones are converted to alkylamides is generally from a minimum of at least 70°C. up to 200°C., preferably from about 90° to 170°C. Further, the method can be undertaken at pressures of from atmospheric up to 300 p.s.i.g. The reaction time is usually about 1 and 24 hours although longer or shorter periods may be employed depending upon the oxygenated polar aprotic solvent used and the temperature conditions employed. Further, the reaction described herein should be undertaken in a substantially anhydrous medium wherein less than about 3 weight percent water is introduced to the reaction. Water if introduced in amounts greater than about 3 weight percent substantially diminishes the yield of amide.

Specific examples of the alkylamides prepared by the instant method include acetamide, propanamide, butanamide, 3-methylbutanamide, pentanamide, hexanamide, octanamide, dodecanamide, pentadecanamide and nonadecanamide.

In another embodiment of the invention a method is contemplated wherein 1-olefins of from 3 to 52 carbons are converted to alkylamides. More specifically, the method involves first contacting a 1-olefin of the formula $R-CH=CH_2$, where R is as heretofore defined, with a mixture of dinitrogen tetroxide and oxygen at a temperature between about -40° and $20^\circ C$. employing reactant mole ratios of olefin to dinitrogen tetroxide to oxygen between about 1:0.5:1 and 1:1.5:30, where the moles of oxygen is at least equivalent and preferably in excess to the moles of dinitrogen tetroxide used. After a reaction time normally between about $\frac{1}{2}$ and 10 hours, a nitroalkylperoxy nitrate of the formula:

is formed where R is as previously described. The nitroalkylperoxy nitrate is thereafter contacted in a second stage with a denitrating agent of the group recited in U.S. Pat. No. 3,557,166 which is herein incorporated by reference. Illustrative of the denitrating agents are dimethylformamide, diethylformamide, dimethylacetamide, dimethylsulfoxide, diethylsulfoxide, tetramethylurea and tetraethylurea. Other denitrating agents include alkylpyrrolidinones such as 1-methyl-2-pyrrolidinone, 1-ethyl-2-pyrrolidinone and 1,4-dimethyl-2-pyrrolidinone. A highly preferred denitrating agent in the present invention is dimethylsulfoxide. The second stage is undertaken employing mole ratios of denitrating agent to peroxy compound of at least 1:1 to about 20:1 at temperatures of between about -60° and $70^\circ C$. to form a nitroketone of the formula hereinbefore described. In the third stage, the nitroketone is contacted in an oxygenated polar aprotic solvent, a highly preferred solvent being dimethylsulfoxide, under the conditions prescribed above thereby thermally converting the nitroketone to an alkylamide.

At the completion of the reaction, the alkylamide formed in the conversion reaction is recovered by cooling the reaction mixture and isolating the resulting solid or by chilling the reaction mixture with water and recovering the crystals so formed. Contacting with water is undertaken at temperatures below $60^\circ C$. to avoid hydrolysis of the amide and is best conducted with iced water. Any unconverted nitroketone along with the oxygenated polar aprotic solvent and diluent, if employed, are separated for use in a subsequent or continuous reaction. The co-product, carbon dioxide, can be recovered, if desired, in the course of the reaction or at the completion thereof by scrubbing the exit gas with an amine base at room temperature. The carbon dioxide can thereafter be recovered by thermally decomposing the aminecarbon dioxide complex. The oxygenated polar aprotic solvent is not consumed in the method and can be suitably reused.

The alkylamide products of this invention are useful as fuel additives, solvents for waxes, dye solubilizers, fuel and lubricant additives, foam stabilizers in synthetic detergents, plasticizers for polymers and as reac-

tion diluents. Further, they are useful as intermediates in the preparation of fabric water repellents and the alkylamides prepared according to the inventive method may be hydrolyzed, dehydrated or hydrogenated to form their corresponding acids, nitriles and amines useful in soaps, cosmetics and fabric softeners.

In order to more fully illustrate the nature of our invention and the manner of practicing the same, the following examples are presented.

EXAMPLE I

A 100 milliliter solution composed of 12.0 grams (0.042 mole) of 1-nitro-2-hexadecanone in dimethylsulfoxide (1.12 mole) was heated to $130^\circ C$. An exotherm occurred accompanied by an evolution of gas causing the temperature to rise to $158^\circ C$. The solution was thereafter maintained at about $150^\circ C$. for a total of 2 hours. 25 milliliter samples were removed every one-half hour and poured into 25 milliliters of ice water. The resulting mixture was filtered and the solids were dried at 100 mm. Hg. and $25^\circ C$. Analysis by infrared and nuclear magnetic resonance of the samples indicated that the product was predominantly pentadecanamide along with some unreacted nitroketone. 2.67 grams of amide were recovered corresponding to a yield of 95 percent.

EXAMPLE II

A solution of 24.0 grams (0.084 mole) of 1-nitro-2-hexadecanone in 90 milliliters of dimethylsulfoxide (1.12 mole) was heated to $100^\circ C$. and the accompanying exotherm raised the temperature to $170^\circ C$. The temperature was thereafter maintained for 2 hours at about $148^\circ C$. whereupon the product was poured into 100 milliliters of ice water and filtered. The solids (29.43 grams) were air dried and analyzed by infrared and nuclear magnetic resonance. The analyses showed the product to be mainly pentadecanamide along with about 5 to 10 percent pentadecanoic acid.

EXAMPLE III

The procedure of Example I was followed except that 1.17 mole of dimethylformamide was substituted for dimethylsulfoxide as the solvent and sampling occurred once every hour. Analyses showed that after 3 hours the nitroketone was converted to the alkylamide.

EXAMPLE IV

A 100 milliliter solution of 12.0 grams (0.042 mole) of 1-nitro-2-hexadecanone and 6.6 grams (0.084 mole) of dimethylsulfoxide in 1,2-dichlorobenzene was maintained at $150^\circ C$. for 6 hours. Samples were periodically removed and analyzed by infrared which showed that after 6 hours no measurable conversion of the nitroketone to the amide had occurred. The procedure was repeated except using 3.3 grams (0.042 mole) of dimethylsulfoxide which gave identical results. This example illustrates that mole ratios of nitroketone to oxygenated polar aprotic solvent of less than 1:3 are inoperative in the inventive method.

EXAMPLE V

The procedure of Example I was repeated except that the reaction was maintained under an atmosphere of argon and the gases collected. Infrared analysis and mass spectrographic analysis revealed the collected gas to be composed of 83.7% carbon dioxide, 9.0% argon, 2.7% carbon monoxide and 1.7% methyl sulfide.

We claim:

1. A method of preparing an alkylamide which comprises contacting an alpha-nitroketone with an oxygenated polar aprotic solvent at a temperature of from about 70°C. to 200°C.

2. A method according to claim 1 wherein said temperature is from about 90° to 170°C.

3. A method according to claim 1 wherein the mole ratio of said nitroketone to said solvent is from about 1:3 to 1:100.

4. A method according to claim 1 wherein the mole ratio of said nitroketone to said solvent is from about 1:10 to 1:50.

5. A method according to claim 1 wherein said contacting is at a pressure of from atmospheric to 300 p.s.i.g.

6. A method according to claim 1 wherein said solvent is dimethylsulfoxide.

7. A method according to claim 1 wherein said solvent is dimethylformamide.

8. A method according to claim 1 wherein said solvent is 1-methyl-2-pyrrolidinone.

9. A method according to claim 1 wherein said solvent is acetone.

10. A method according to claim 1 wherein said solvent is dimethylacetamide.

10

11. A method according to claim 1 wherein said contacting is conducted in the presence of an inert liquid diluent boiling between about 80° and 200°C.

12. A method according to claim 1 wherein said alpha-nitroketone corresponds to the formula:

13. A method according to claim 1 wherein said nitroketone is 1-nitro-2-propanone and where said alkylamide is acetamide.

14. A method according to claim 1 wherein said nitroketone is 1-nitro-2-hexadecanone and where said alkylamide is pentadecanamide.

15. A method according to claim 1 where carbon dioxide formed as a co-product is recovered.

16. A method of preparing an alkylamide which comprises (1) nitrooxidizing a 1-olefin by contacting with dinitrogen tetroxide and oxygen to form a nitroalkyl-peroxy nitrate, (2) contacting said peroxy nitrate with a denitrating agent to form an alpha-nitroketone and (3) contacting said nitroketone with an oxygenated polar aprotic solvent at a temperature of from about 70°C. to 200°C.
